UNITED STATES PATENT OFFICE.

MORRIS P. BRAY, OF NEW HAVEN, CONNECTICUT, ASSIGNOR TO DAVID H. FANNING AND THEODORE C. BATES, OF WORCESTER, MASSACHUSETTS.

CORSET.

SPECIFICATION forming part of Letters Patent No. 240,082, dated April 12, 1881.

Application filed January 26, 1881. (Model.)

To all whom it may concern:

Be it known that I, MORRIS P. BRAY, of New Haven, in the county of New Haven and State of Connecticut, have invented a new Improvement in Corsets, and I do hereby declare the following, when taken in connection with the accompanying drawings and the letters of reference marked thereon, to be a full, clear and exact description of the same, and which 10 said drawings constitute part of this specification, and represent, in—

Figure 1, a front view of the front section of the corset; Fig. 2, transverse section of the part complete; Figs. 3 and 4 illustrate the 15 method of making said section.

This invention relates to an improvement in the front or clasp section of a corset, the object being to construct the clasp double or one steel partially overlapping the other, and from 20 a single thickness of fabric—that is to say, without stitching at the edge or making an overlapping pocket; and the invention consists in the construction, as hereinafter described, and particularly recited in the claim.

25 I first cut the front section from a single piece of fabric of sufficient width and shape that when doubled it will form the complete section.

A B represent the folded section of the part 30 a, being the line upon which the part is doubled. Upon the under side of the portion B of this part I stitch a strip of fabric, b, by a line of stitches parallel with the doubled edge, a, and distant therefrom less than the width 35 of the underlying or re-enforcing steel K. I then turn the portion A beneath the strip b, as seen in Fig. 4, and turn the part B upward, so as to expose the edge of the strip b. I then 40 run a line of stitches, e, through the edge of the part b and the part A, which forms a pocket

for the edge or underlying steel, as seen in Fig. 4. I then turn the part B down upon the part A, and distant from the line of stitches d equal to the width of the principal steel h, I run a line of stitches, i, parallel with the edge a, 45 which forms the pocket for the principal steel h, as seen in Fig. 2. Thus the front edge or section of the corset is made from a continuous piece of fabric without stitching at the edge or overlaying a pocket on the surface of the 50 material. The re-enforcing-steel is held in close contact with the principal steel h, and cannot be displaced without destroying the corset.

I prefer to make the whole of the front section, as shown in Fig. 1, in one piece, by giving it the required shape at the rear edge, yet 55 it may be cut with the rear edge straight or parallel with the front edge and furnished to the trade as a clasp.

I do not wish to be understood as broadly 60 claiming a re-enforced or partly overlying steel in a corset, as such I am aware is not new; but

What I do claim is—

The herein-described improvement in cor- 65 sets, consisting of the front edge made from the folded section of fabric A B, doubled at the edge a, with the strip b, stitched upon the inside of the part B, parallel with the edge a, and on a line distant from the edge less than 70 the width of the re-enforcing-steel K, the rear edge of this strip b, stitched to the underlying part of the fabric to form a pocket for the re-enforcing-steel K, then the two parts A B 75 stitched together to form a pocket for the principal steel h, substantially as described.

MORRIS P. BRAY.
